[57] ABSTRACT

A shift register in the form of a thin film magnetizable material defining a first zone of relatively low coercivity surrounded by a second zone of relatively high coercivity with the first zone extending in the direction of the axis of relative difficult magnetization and being divided from the second zone or respective opposite sides by first and second boundaries has each boundary formed by periodically repeating division formed by a first segment comprising a ridge inclined to the difficult axis by an angle of the order of 45° and connected to the remaining segment of the division in the shape of a finger having a direction parallel to the easy axis with the ridge having a variation in slope between its two ends, thus facilitating the circulation of nucleated domains.

IMPROVED REGISTER FOR PROPAGATING MAGNETIC DOMAINS -

BACKGROUND OF THE INVENTION FIELD OF THE INVENTION

Like the object of parent U.S. Pat. No. 3,739,358, the invention comes within the branch of memory devices having thin polycrystalline anisotropic magnetic layers in which a magnetic zone having low coercivity surrounded by a basic layer having higher coercivity constitutes a medium in which a magnetic domain progresses step by step under the control of a clock. It concerns an improvement in the trace defining the magnetic zone having low coercivity.

DESCRIPTION OF THE PRIOR ART

The parent patent describes a register for propagating magnetic domains which has the general form of a strip of layer having low coercivity defined on its two long edges by irregular contours having a characteristic shape, with divisions or chambers, adapted for receiving a nucleated magnetic domain at one end of the strip, for example, the left-hand end, which propagates in a broken line according to the mode: division on the upper edge - division on the lower edge - division on the upper edge - division on the lower edge . . . advancing from left to right, as a function of a clock pulse. The elementary layout of the irregular contour comprises a ridge inclined by an angle α on the longitudinal axis of the register or difficult magnetisation axis (where α is in the order of 45°), connected at its end further from the axis to a division in the shape of a finger, whose axis is perpendicular to the axis of the register.

It has been observed experimentally that this arrangement of the ridge in the form of a rectilinear segment could bring about the nucleation of interference domains in the adjacent finger-shaped division.

SUMMARY OF THE INVENTION

To overcome that disadvantage, the present addition provides for a non rectilinear shape to be imparted to said ridge, having one or several irregularities in slope capable of cancelling the interference nucleation effect.

The invention will be described in detail according to several forms of embodiment, with reference to the accompanying schematic drawings.

BRIEF DESCRIPTION OF THE DRAWINGS

FIG. 1 shows, by way of reference, a portion of a register for the propagation of magnetic domains according to the parent patent.

FIG. 2 shows a first modification in the ridge of the contour, comprising a relatively long first rectilinear segment followed by a greater slope segment.

FIG. 3a shows a second modification comprising, at (a) two short segments following a long segment.

FIG. 3b shows a further modification where the short segments are replaced by a continuous curve.

FIG. 4a shows a fourth modification where two end segments having a great slope are connected by a middle segment having a slighter slope.

FIG. 4b shows a fifth modification where the original rectilinear ridge is replaced by a curve having a reversal in direction.

DESCRIPTION OF THE PREFERRED EMBODIMENT

FIG. 1. A portion of a register according to the parent patent is shown, with an irregular contour on the upper edge, whose points A_0 , E_0 , D_0 , C_0 , A'_0 , have had references corresponding to those in the parent patent assigned to them. The reference F_0 on the ridge $C_0 A'_0$, has been added at the same height as E_0 .

The direction of the easy axis has been marked with an arrow f_1 ; the direction of the difficult axis has been marked with an arrow f_2 . The points of the contour of the lower edge have not been referenced.

15 The discontinuity of the magnetisation along the ridge $A_0 E_0$ gives rise to magnetic poles, which set up a demagnetising field pointed downwards below $A_0 E_0$ and pointed upwards above $A_0 E_0$. The division $E_0 D_0 C_0 F_0$ is referenced S_0 herebelow. The detailed examination of that demagnetising field reveals, in a zone in the vicinity of E_0 , that is, at the base of the division S_0 , a component of a magnetic field, along the easy axis f_1 , of several oersteds, pointed upwards, therefore favourable to the increase of the domains in the division S_0 , as well as a component also having an intensity of several oersteds along the difficult magnetisation axis f_2 . The simultaneous action of these two components of magnetic fields combined with the action of the magnetic fields induced by the conductors (not shown) ensure the operation of the register, sets up favourable conditions for the nucleation of interference domains in the lower part of the division S_0 . The magnetic poles on the ridge $A_0 E_0$ have a density σ_0 .

An examination of the magnetic field set up by the inclined ridge $A_0 E_0$ which has, for example, a length of 75 microns charged with magnetic poles, has made a component of 5 Oe appear at the base of the division S_0 along the easy axis. That component is added to the magnetic field of the control currents, which is in the order of 11 Oe along the easy axis, gives a great resulting magnetic field, in the vicinity of the nucleation field in the division, this decreasing the operating margins of the register below the reliability threshold.

45 FIG. 2. To overcome this state of affairs, FIG. 2 shows an upper irregular contour (the only one shown to simplify the figure) comprising a first rectilinear segment $A_1 G_1$, making an angle α_1 with the difficult axis f_2 of the register, followed by a second shorter rectilinear segment $G_1 E_1$ forming an angle α_2 with the difficult axis, a division in the form of a finger E_1 , $D_1 C_1 F_1$ (division S_1) corresponding exactly to the division S_0 in FIG. 1.

50 A value in the order of 45° to 60° will be attributed to α_1 ; a value greater than α_1 will be attributed to α_2 . The ridge $G_1 E_1$ will then bear magnetic poles having a density σ_1 less than σ . (figure 1). The result of this is that the demagnetising produced by that ridge will therefore be less in the case of FIG. 1, thus reducing the dangers of interference nucleation at the lower part of the division S_1 .

55 For example, for a ridge $A_1 G_1$ having a length of 60μ , where $G_1 E_1 = 15\mu$ and $\alpha_1 = 60^\circ$ and $\alpha_2 = 75^\circ$, the demagnetizing field produced at the base of the division S_1 will have half the intensity of the case in FIG. 1.

60 FIGS. 3a 3b show two variants, close to each other, of the arrangement according to FIG. 2.

In variant FIG. 3a, the line A1 G1 E1 having two segments in FIG. 2 is replaced by a line having three segments A2 G2 G'2 E2, whose slopes go increasing from A2 towards E2.

In variant FIG. 3b, the two segments G2 G'2, G'2 E2, are replaced by an infinite number of segments, this leading to a first rectilinear segment A3 G3 followed by a curve G3 E3 tangent to the segment A3 G3 at G3 and tangent to the segment E3 D3 at E3. The density of the magnetic poles borne by that curve varies from α_3 at G3 to zero at E3, thus eliminating the possibilities of interference nucleation at the base of the division S3.

The relative lengths of the lines A3 G3 and G3 E3 are not critical. An embodiment may also be provided in the form of a curve A3 E3 forming an angle α_1 with the longitudinal axis at A3 and tangent at E3 to the straight line E3 D3.

FIG. 4a and FIG. 4b show two variants close to each other.

In the variant FIG. 4a, the link between the point A4 and the point E4 is provided by three segments A4 G4 having a slope α_3 , G4 G'4 having a slope α_4 , G'4 E4 having a slope α_5 , where $\alpha_3 > \alpha_4 < \alpha_5$.

That geometrical configuration, which is more difficult to produce than the previous ones, enables a better distribution of the magnetic charges and consequently a better guiding of the domains during propagation.

In the variant FIG. 4b, the sharp angles between the segments are replaced by rounded portions ensuring better transition between the densities of magnetic poles of the various segments. A curved line having a reversal in direction is finally obtained.

S4 designates the division E4, D4, C4, F4; S5 designates the division E5, D5, C5, F5.

The dimensions of the various segments are not critical. The following could be taken by way of a non-

limiting example: A4 G4 = 30 μ , G4 G'4 = 30 μ , G'4 E4 = 15 μ , where $\alpha_3 = 75^\circ$, $\alpha_4 = 60^\circ$ and $\alpha_5 = 75^\circ$.

We claim:

1. In a shift register including thin film magnetizable material defining a first zone of relatively low coercivity surrounded by a second zone of relatively high coercivity with said first zone extending in the direction of the axis of relatively difficult magnetization and at right angles to the axis of relatively easy magnetization and being divided from the second zone on respective opposite sides by first and second boundaries, each boundary being formed by periodically repeating divisions comprising a ridge inclined to the longitudinal difficult axis of the register and being connected to an adjacent chamber in the shape of a finger having a direction parallel to the easy axis, the improvement wherein: said ridge has variations in slope between its two ends.

2. The register for propagating domains according to claim 1 wherein: said ridge comprises at least two rectilinear segments, whose slopes increase towards the division in the shape of a finger.

3. The register for propagating domains according to claim 1, wherein: the ridge comprises a first rectilinear portion and a second curved portion, tangent on the one hand, to the said rectilinear portion and tangent on the other hand to the direction of the easy axis.

4. The register for propagating domains according to claim 1, wherein: said ridge is subdivided into three respective segments of slopes α_3 , α_4 , α_5 where $\alpha_3 > \alpha_4 < \alpha_5$.

5. The register for propagating domains according to claim 1, wherein: the ridge takes the form of a curved line having a reversal in direction, with a tangent parallel to the easy axis at one end.
